UNITED STATES PATENT OFFICE.

MILO D. LOOMAN, OF ORCUTT, CALIFORNIA, ASSIGNOR OF ONE-HALF TO EDWARD E. FORBES, OF ORCUTT, CALIFORNIA.

METHOD OF CONVEYING OIL.

1,192,438.

Specification of Letters Patent. Patented July 25, 1916.

Application filed March 25, 1914. Serial No. 827,133.

To all whom it may concern:

Be it known that I, MILO D. LOOMAN, a citizen of the United States, residing at Orcutt, in the county of Santa Barbara and State of California, have invented certain new and useful Improvements in Methods of Conveying Oil, of which the following is a specification.

The present invention relates to a method 10 of conveying oils or the like through pipes or conduits, by passing the same over relatively stationary bodies of water held within the lower portion or bottom of the pipe.

In the accompanying drawings forming 15 a part of this specification and in which like numerals are employed to designate like parts throughout the same, Figure 1 is a side elevation of a pipe embodying my invention, Fig. 2 is a central longitudinal sectional view through the same, Fig. 3 is a transverse sectional view taken on line 3—3 of Fig. 1, and, Fig. 4 is a similar view taken on line 4—4 of Fig. 1.

In the drawings, the numeral 5 designates 20 my conduit, as a whole, which is provided at longitudinally spaced intervals with outwardly bulging pockets or portions 6, having curved tapered ends 7, as shown. Between the outwardly bulging pockets are 25 the normal portions 8 of the pipe, having a much smaller diameter, in comparison with the bulging pockets 6, as shown. I have found that the best results are obtainable by having the outwardly bulging pockets or 30 portions 6 of a substantially greater length than the diameter of the normal portions 8 of the pipe, as shown. The normal portions are shorter in length than the pockets or 35 portions 6, as shown. Each section of the pipe is so cut or made that its end is in the form of an outwardly bulging portion or pocket 6', preferably exteriorly screw-threaded, as shown at 9, for connection with 40 one end of a corresponding pipe.

In the practice of the method, water is 45 preferably first forced or pumped through the same whereby it will be collected in the lower portions of the outwardly bulging

portions or pockets 6, forming a series of water puddles 10 which are connected and 50 form in effect a continuous lower supporting stratum of water. The outwardly bulging pockets 6 prevent this lower stratum of water from flowing or moving longitudinally within the pipe. The oil to be passed 55 through the pipe is now fed into the same, and floats upon the lower continuous stratum of supporting water 10, whereby the oil is allowed to pass with the least friction. It is thus apparent that the oil is 60 passed over a plurality of stationary bodies of water, arranged in the bottom of the conduit or pipe, such bodies of water being more or less collected.

In conveying some oils containing a high 65 amount of water, it is not necessary to first fill the pockets 6 with water, as the same will be filled with the water carried by and precipitated from the oil. However, in each case, the pockets become filled with the water, forming in effect a continuous lower supporting stratum of water, over and upon 70 which the oil floats while passing longitudinally through the pipe.

Having described the invention, I 75 claim:

1. The method of conveying oil, which consists in passing the oil over a relatively 80 stationary track of water held in the bottom of a conduit.

2. The method of conveying oil, which consists in passing the oil over a plurality of more or less connected relatively stationary bodies of water held in the bottom of a conduit.

3. The method of conveying oil, which consists in passing the oil over a plurality of relatively stationary bodies of water held in a conduit.

In testimony whereof I affix my signature in presence of two witnesses.

MILO D. LOOMAN.

Witnesses:

A. F. FUGLER,
E. E. FORBES.
